UNITED STATES PATENT OFFICE

WILLIAM A. WATSON, OF NEW HAVEN, CONNECTICUT

VALVE UNIT FOR PLAYER PIANOS

Application filed April 24, 1928. Serial No. 272,470.

This invention relates to valve structures for pneumatically controlled mechanisms, and especially to valve mechanisms used in connection with player pianos. While I have shown my improved device in connection with what is termed single valve devices, it will be understood that my improvements are not restricted in all aspects to this class of mechanism, but are applicable in other 10 relations as well.

The invention is shown in connection with metallic valve units wherein the pouch chamber and valve chamber are formed as an integral structure of metal, so that they may 15 be readily and cheaply manufactured and at the same time be readily assembled with the wind chest of the instrument to provide a device which will be efficient in operation.

It is obvious that it is desirable to keep to a 20 minimum the amount of air that must be exhausted or drawn into the exhausting device when a player pneumatic is collapsed. As prior to the collapsing of the pneumatic the air must be drawn from the valve chamber, which is in communication with the pneumatic, it is desirable that this valve 25 chamber be as small as possible consistent with the other factors which must be taken into consideration.

It is also obvious that it is necessary to 30 provide a pouch or valve operating pneumatic which shall be of sufficient size to have the required power to operate the valves quickly and snappily without appreciable 35 drag.

One object of my invention, therefore, is 35 the provision of a combined valve chamber and pouch chamber, such that the valve chamber will be reduced in size with relation to 40 the pouch chamber, whereby the amount of air which must be drawn from the valve chamber will be reduced to a minimum.

Another object of my invention is to provide 45 a combined pouch chamber and valve chamber, wherein the parts are so proportioned that the valve chamber is of smaller diameter than the pouch chamber, whereby a relatively large pouch pneumatic may be 50 used and at the same time, the air which

must be exhausted from the valve chamber will be kept to a minimum.

Another object of my invention is to provide an integrally formed unit, which will comprise both a valve chamber and a pouch 55 chamber, and having an exterior shoulder which may be lodged against the wind chest.

Another object of the invention is to provide a communicating pouch chamber and valve chamber separated by a partition, forming 60 a valve seat member, the partition being adjustable to regulate the position of the seated valve.

To these and other ends, the invention consists in the novel features and combination of 65 parts to be hereinafter described and claimed.

In the accompanying drawings:

Fig. 1 is a sectional view of a wind chest, 70 valve unit and player pneumatic embodying my invention;

Fig. 2 is a side elevational view of the valve unit detached from the wind chest;

Fig. 3 is a front elevational view of the 75 parts shown in Fig. 1;

Fig. 4 is an enlarged sectional view of the valve unit.

I have shown in Fig. 1 of the drawings, a wind chest 10, which may be supported in any suitable manner, having mounted thereon a junction box 11 in which are joined the parts 12 and 13 of the tracker tube. The lower end of the tracker tube is inserted through an opening 14 at the back of the 80 wind chest.

At the lower side of the wind chest is secured a striker pneumatic 15, being held in place by means of a screw 16, inserted through an extension 17 upon the bottom wall 85 of the wind chest.

Upon its front side the wind chest is provided with a plurality of openings 18 through which are inserted a part of each of the valve units, designated as a whole by the reference character 19.

These valve units, as shown more particularly in Figs. 1 and 4, comprise a pouch 90 chamber 20 and a valve chamber 21, the pouch chamber 20 having an opening 20a through the side wall thereof, whereby one side of a 100

pouch 22 within the chamber 20 is exposed to pressure obtaining within the wind chest. On the other side of the pouch 22 is a chamber 23 with which the tracker tube communicates, and the pouch is provided with a bleed opening 24, the bleed opening being constituted by an opening through the riveted eyelet which secures the valve stem follower 24^a to the pouch.

- 10 The valve unit, as previously stated, is integrally formed from a single piece of metal, and it will be noted that at the junction of the valve chamber and pouch chamber the wall of the unit has been displaced outwardly, and thereafter the two folds pressed together to form a two-ply annular shoulder or flange 26 which projects from the unit. As shown in Fig. 4, the valve chamber lies to the left of this shoulder, and it is reduced in 15 diameter with respect to the pouch chamber. That is, the external shoulder is of greater dimension at the left-hand side thereof than at the right.

10 A partition 27, forming a valve seat member, is inserted into the unit and lodged against the inwardly projecting portion of the shoulder 26. This member is cup-shaped in form so as to provide an annular flange 28, which lies against the side wall of the pouch 25 chamber. At its central portion it is provided with an opening 29, and a guide member 30 for the valve stem 31, upon which are mounted the valves 32 and 33, the former controlling the opening 29 and the latter controlling an atmospheric inlet opening 34 at the left-hand end of the valve chamber. It will be noted that this partition while shown as lodged against the internally projecting part of the shoulder 26, may be moved to the right 40 to any desired extent and secured in place by brazing, soldering, or the like, so as to adjust the position of the seated valve. The position shown is, of course, the extreme left-hand position of this member. If it is desired 45 to place it in a position to the right of that shown, a suitable spacing device such as a washer or the like may be placed against the shoulder and the valve seat member lodged against the washer.

50 It will be observed that the shoulder 26 projects outwardly to a considerable extent, both from the pouch chamber 20 and the valve chamber 21. As shown in Fig. 1, when the unit is inserted in the opening in the wind chest, it enters as far as this shoulder which lodges against a washer 35, disposed between this shoulder and the wall of the wind chest, so as to make an air-tight connection. It will be apparent that the parts may thus be assembled very easily and quickly, and at the same time the joints will be effectively sealed. This shoulder permits the pouch chamber to enter the wind chest to the 55 desired extent so that the opening 20^a is en-

tirely therewithin and the pouch chamber will be exposed to the wind chest pressure.

The valve chamber is provided with a thimble or the like 36, through which it communicates with the interior of the striker 70 pneumatic 15, by means of a collar 37, which is secured to the pneumatic and telescopes over the thimble 36.

The valve unit is pressed against the wind chest by means of the lugs 38 and 39, which 75 may be tightened down by the nuts 40.

While I have shown and described a preferred embodiment of my invention, it will be understood that it is not limited thereto in all of its details, but is capable of modification and variation within the spirit of the invention and within the scope of the appended claims.

What I claim is:

1. A valve unit comprising a hollow body, 80 the side wall of the body, at a point intermediate its ends, being folded outwardly to provide an external flange and then folded inwardly to extend beyond the base of the flange and provide an internal shoulder, and 90 a partition lodged against the internal shoulder dividing the interior of the body into a pouch chamber and a valve chamber.

2. A valve unit comprising a hollow body, 95 the side wall of the body, at a point intermediate its ends, being folded outwardly to provide an external flange and then folded inwardly to extend beyond the base of the flange and provide an internal shoulder, and 100 a partition lodged against the internal shoulder dividing the interior of the body into a pouch chamber and a valve chamber, and the valve chamber being small in cross-sectional area relatively to the pouch chamber.

3. A valve unit comprising a hollow body 105 having a continuous side wall extending from end to end thereof, the wall being folded outwardly and then inwardly at a point intermediate the ends, and the folds being pressed together to form an external 110 flange extending around the body, and one of the folds being extended inwardly to form an internal shoulder, and a valve seat lodged against said shoulder.

4. In combination, a wind chest having an 115 opening therein, a valve unit comprising a pouch chamber, and a valve chamber having an external shoulder formed thereon, with the pouch chamber disposed at one side of said shoulder, and said pouch chamber 120 being mounted in the opening in the wind chest with the shoulder lodged against the edge of the opening.

5. A valve unit, comprising a pouch chamber and a valve chamber having integral side 125 walls, and an externally projecting shoulder formed at the junction of said chambers, and a wind chest having an opening in which the pouch chamber is mounted, with the shoulder lodged against the edge of the opening and 130

there being an opening through the side wall of the pouch chamber whereby the interior thereof is in communication with the wind chest.

5 6. A valve unit comprising a hollow body having a side wall extending continuously from end to end thereof, the wall being displaced outwardly at an intermediate portion of the body and then folded inwardly to
10 form a two-ply externally projecting flange, the part of the wall folded inwardly being of greater area than that folded outwardly to form an internal shoulder, and to effect a reduction of cross sectional area in that part
15 of the body beyond said fold.

7. A valve unit comprising a pouch chamber, the wall of said pouch chamber being folded outwardly at the upper end of the chamber to form an external shoulder, then
20 folded inwardly beyond the chamber wall to form an internal shoulder, and then continued in a longitudinal direction to form a valve chamber reduced in cross sectional area relatively to the pouch chamber.

25 In witness whereof, I have hereunto set my hand this 21st day of April, 1928.
